UNITED STATES PATENT OFFICE.

CARL GUSTAF SMITH, OF STOCKHOLM, SWEDEN.

MACHINE FOR SPLITTING OF STONES OR THE LIKE.

Application filed December 3, 1924, Serial No. 753,553, and in Sweden December 19, 1923.

This invention relates to improvements in stone splitting machines of that type, which is provided with a hammer arranged on a spring shaft, said shaft being fulcrumed in the machine frame. Below the hammer there is a massive foundation frame or block carrying a steel anvil for supporting the block of stone to be split.

In such a machine considerable difficulties have been experienced in manufacturing the devices appertaining to the shaft, so as to render them capable of resisting the tremendous shocks produced by the blows of the hammer.

The object of the invention is to obtain a device of the aforesaid kind, in which the shaft is effectually protected against breaking or other damage which might occur from the shocks mentioned above.

A preferred example of the invention is shown in the accompanying drawings, in which:

Figure 1 shows a side view, partly in section, of a stone splitting machine, Fig. 2 a plan view of the same. Figure 3 shows a section of the head of the hammer on the line III—III, Fig. 1. Figure 4 shows a section on the line IV—IV, Fig. 1, on an enlarged scale. Figures 5, 6 and 7 show details.

On the frame 1 of the machine there is secured a shaft 2. A friction sheave 3 is mounted for rotation on said shaft and adapted to be frictionally engaged by a smaller friction sheave 4, secured to a shaft 5. Said shaft 5 is journaled in two movable arms 6, and on one side of sheave 4 there is located a gear wheel 7, fixed on shaft 5 and meshing with a pinion 8, secured to shaft 9. Shaft 9 is mounted for rotation in bearings on the machine frame, and constitutes the driving shaft of the machine. On shaft 9 there is secured a fly wheel 10, which may be used as a driving belt pulley. Wheels 4 and 7 are located between the two movable arms or links 6, which are fulcrumed on shaft 9 and are, by means of link rods 12, connected to a shaft 11, mounted for rotation in the machine frame. The connection between link rods 12 and shaft 11 comprises levers 13, fixed on shaft 11 and pivotally connected to levers 13. A treadle 14 is secured to shaft 11 and provided with a counter-weight 15.

The spring arm 16 of the hammer is fulcrumed on shaft 2. Said arm 16 is built up

of a number of flat springs, secured together and fixed on a rigid member 17, said member 17 being fulcrumed on shaft 2. Screw bolts 19 and a cap plate 18 are used for securing spring arm 16 to the rigid member 17. Said member 17 is given the shape of a fork, one branch being located on each side of sheave 3. A connection is formed between sheave 3 and member 17, by means of a rod or a bolt 20, located in webs 21 of member 17, one extending from each fork branch of said member. Bolt 20 passes through sheave 3 above one of the arms 22 of said sheave, the arms being provided with a projection 23 adapted to engage the bolt. On each of the arms of sheave 3 there is a similar projection in order to make possible the use of any one of said arms. The arrangement is such, that when the left portion of the sheave moves in the falling direction of the hammer, the sheave will turn independently of the hammer. On sheave 3 there is fulcrumed on a pin 25 a strap 24, the middle portion of said strap as shown in Fig. 1 passing around one of the arms of sheave 3, preferably the one opposite to the arm co-acting with bolt 20. A connecting member 26, secured to the machine frame 1 is connected to strap 24 by means of a pin 28, located in hooks 27 of member 26 and normally resting in two recesses of strap 24. Said pin 28 is connected to a spiral spring 29, which is secured to the machine frame by means of a securing bolt 30, which may also serve to adjust the tension of spring 29. When turning the sheave in such a direction that the hammer will be raised by the co-action of arm 22 and bolt 20, the strap 24 will be forced downward from pin 28, which will remain supported by hooks 27.

A buffer is located below the spring shaft 16 of the hammer. Said buffer comprises a support or base 31 mounted on a foundation plate or block 32. Said support is threaded on the inside and a socket 34 having an operating handle or wheel 35 is screwed into same. In this socket there is longitudinally movable a rod 36, provided at its lower end with a stop washer 38 and at the upper end with a buffer head 37 acted upon by a spring 39.

The hammer head 40 is secured to spring arm 16 by means of four elastic members 41 made of rubber or any other suitable material. Of these elastic members 41, two are located at the upper side of the arm and

the other two at the lower side. Cross pieces 42 of iron or the like are secured to arm 16 between the elastic members 41, the whole being introduced into a hole in the hammer, in the usual manner, and axially secured by means of two plates 43 and 44. The cross dimensions of the arm 16 and the hole in the hammer are alike. The hammer head is provided with a steel tool 45, which may be provided with an edge, as shown on the drawing, or may be made obtuse or convex or any suitable shape. Below the hammer on foundation block 32 there is mounted a steel anvil 46, which may be given different shapes in the same manner as steel tool 45. The foundation block 32 may be built up of solid stone or reinforced concrete or any other suitable material. It being a matter of great importance that members 45 and 46 are accurately adjusted with relation to each other, it is advisable to connect the machine frame to the foundation block 32 by means of girders 47.

On each side the hammer head 40 is provided with a guide 48, the guide on the fore side of the head not being shown on the drawing Fig. 1.

To make it possible to stop the hammer and retain it in different positions, a frictional pawl may be provided, said pawl acting on the sheave 3 and being fitted with a hand operating gear of known design.

The machine is operated and brought into function by means of the treadle 14. The treadle being forced down, the friction sheave 4 will be brought into driving contact with the larger sheave 3, the treadle pressure being transmitted by means of links 12. The sheave 4 rotating, the hammer will be raised during the rotation of sheave 3, as long as sheaves 3 and 4 are in frictional connection with each other. According to the principle bearing on the design of this machine, the hammer will be raised as long as the treadle is held down. Afterwards, when the hammer falls and strikes a stone block placed on the lower steel anvil, the force of the hammer will be subdued by the action of the buffer, and sheave 3, still under the influence of the inertial force, will be checked by spring 29. The hammer being yieldingly connected to the arm 16, will thus be able to deliver its blow on the block with the least possible disturbance to the shaft, sheave and other connections, said connections also being spared from the ac-

tion of those powerful shocks which would occur if the hammer, the shaft and the sheave were rigidly connected to each other. The buffer as well as the spring 29 must be dimensioned in such a manner that the hammer will be raised quickly from the stone block owing to the tension of the spring 39, and that sheave 3 will be turned into its initial position for raising the hammer. The buffer is vertically adjustable, in such a way that the arm 16 may be acted upon at the right moment, and not too early. Such an adjustment is also necessary on account of the wearing down of the steel members 45 and 46.

Within the scope of the invention, the details of the machine may be varied as to size, form, arrangement and manner of using, without departing from the spirit of the invention as set forth in the appended claims.

Having now described the nature of my invention, what I claim is:

1. In a stone splitting machine the combination of a hammer provided with an opening therethrough, a vertically movable spring arm having one end thereof extending into said opening, the arm being of the same width as that of the opening but of considerably less thickness than the height of said opening, resilient members between said arm and the top and bottom of said opening, and means for preventing withdrawal of said arm from the opening, said means comprising a pair of plates secured to the hammer and closing the ends of the opening and a pair of metallic members secured to the arm between said resilient members.

2. A stone splitting machine, comprising in combination, an arm freely pivoted for angular movement in a vertical plane, a hammer secured to said arm at one end thereof, rotatable means effective during rotation in one direction to engage and raise said arm thereby to elevate the hammer, said means being adapted to release the arm thereby to permit the hammer to fall free of its elevating means when the rotation thereof ceases, and a resilient buffer disposed in position to check the motion of said elevating means when the latter is rotating in the direction opposite to its hammer-raising direction.

In testimony whereof I have signed my name to this specification.

CARL GUSTAF SMITH.
